DESIGN FOR A GALOSH

Harvey B. Richards, Lake Bluff, Ill., assignor to Richards, Boggs & King, Inc., Chicago, Ill., a corporation of Illinois

Application September 17, 1937, Serial No. 71,662

Term of patent 7 years

To all whom it may concern:

Be it known that I, Harvey B. Richards, a citizen of the United States, residing at Lake Bluff, in the county of Lake and State of Illinois, have invented a new, original, and ornamental Design for a Galosh, of which the following is a specification, reference being had to the accompanying drawing, forming a part thereof.

Figures 3 and 4 are bottom and front views respectively.

I claim:

The ornamental design for a galosh substantially as shown.

HARVEY B. RICHARDS.
